FLAG UNIT FOR AN AUTOMOBILE OR THE LIKE

Howell D. Morris, Scranton, Pa.

Application February 7, 1956, Serial No. 40,065

Term of patent 3½ years

(Cl. D29—17)

FIG. 1.

FIG. 2.

Fig. 1 is a front elevational view of a flag unit, showing my new design.

Fig. 2 is a rear elevational view thereof.

The flag elements are of conventional thickness.

The dominant features of my design reside in the portions shown in full lines in the drawing.

I claim:

The ornamental design for a flag unit for an automobile or the like, substantially as shown and described.
